(57) CLAIM

The ornamental design for a breather head bracket terminal, as shown and described.

DESCRIPTION

FIG. 1 is a top plan view of a breather head bracket terminal showing my new design;

FIG. 2 is a front elevational view thereof;

FIG. 3 is a rear elevational view thereof;

FIG. 4 is a right elevational view thereof; and,

FIG. 5 is a bottom plan view thereof.

The broken line showing in FIGS. 1, 2, and 5 is for illustrational purposes only and forms no part of the claimed invention.
